UNITED STATES PATENT OFFICE

WALTER H. STRAW, OF DEVON, CONNECTICUT

STOCK AND DIE

Application filed March 14, 1931. Serial No. 522,681.

My invention relates to new and useful improvements in stocks and dies, such as are used for thread cutting and more particularly to that class of stocks and dies, including dies having a plurality of cutting faces, whereby the same may be adjusted to different positions to present different cutting faces, and to be used in cutting threads on pipes and bolts of different diameters.

10 An object of my invention is to provide a stock having a pair of specially designed dies, each having three or more cutting faces, and to mount the same for vertical rotary movement in the stock, whereby like cutting faces of the two dies may be brought to register, one with the other, for joint threading operations.

20 A further feature of the invention is to provide for horizontal adjustment of the said dies whereby they may be set in proper relative spaced relation better to accommodate different size pipe, and to cut suitable threads thereon.

25 Another object of the invention is to provide extended guard flanges on the stock, one on each side of the dies, better to protect the same from injury during handling, and also to provide ways between which the cutting arms of the dies are guided during adjustment and for supporting, against rotation after being positioned.

30 With these and other objects in view, the invention resides and consists in the construction and novel combination and arrangement of parts hereinafter more fully described, illustrated in the accompanying drawing, and pointed out in the claims hereto appended, it being understood that various changes 35 in the form, proportions, size, and minor details of construction within the scope of the claims may be resorted to without departure from the spirit, or sacrificing any of the advantages of the invention.

40 Similar characters of reference denote like or corresponding parts throughout the several figures of the accompanying drawing forming a part of this specification and upon which

50 Fig. 1 shows a plan view of my improved

stock and dies assembled as for use, the handles being broken away;

Fig. 2 is a side elevation, on a slightly enlarged scale, of approximately one half of the stock, and one of the dies shown in Fig. 1;

Fig. 3 is a central vertical longitudinal section of that much of the stock and one of the dies shown in Fig. 2;

Fig. 4 shows an enlarged central vertical cross section taken on line 4—4 of Fig. 1; and

Fig. 5 is a further cross section, taken on line 5—5 of Fig. 1.

It will be noted from the illustrations and description of this invention that it includes duplicate sets of die mechanisms, one in each end portion of the stock, the opening to receive the pipe to be threaded, being formed central in this stock intermediate of the said mechanisms and adjacent the operative faces of two thread cutting dies. Therefore, similar reference characters will be used to designate the duplicate parts in the two end portions of the stock.

10 represents the stock as a whole, and which as will be seen in Fig. 1, is of an oval, elongated form and includes a cylindrical extension 11 on each end portion, having a threaded socket therein for receiving the usual type of attached handles 12. This stock also includes parallel, longitudinal 15 spaced apart sides 13 which are substantially alike in construction. In this connection it will be noted that flanges 14 extend out from the top edge of the end portions of these sides better to protect the dies 15 adjustably mounted therebetween. Each of these dies are rotatably mounted, upon a bolt 16 forming a pivotal member, intermediate the said sides and flanges and are adapted for both 20 sliding and rotatable adjustment. An opening 17 is formed through the bottom of each end portion of the stock to provide room for the dies. A third or central hole 18 is also provided through the base of this stock, intermediate of the two said openings 17, through which the pipe to be threaded is positioned for engagement by the dies. The stock may be further provided with ribs 19 and 20 upon the under side to strengthen and

25 support the same.

The dies 15, as shown in the drawing are provided with three or more radially disposed thread cutting arms, but they may obviously be provided with a greater number if desired, 5 each of which would be substantially alike, except that the threading dies thereof would be formed larger or smaller for cutting larger or smaller pipe. These arms 21 are of the same thickness as the hub portions of the 10 dies and there is a contacting surface 22 formed on the hub of the dies intermediate of the said arms, for the engagement of an adjusting screw, as will again be referred to.

23 represents ribs which are formed upon 15 the inner opposite walls of the before mentioned sides adjacent to the central opening in the stock, and includes a flat top bearing surface upon which rests the under surfaces of an arm of each die. Plates 24 are secured 20 to the top edge of the sides immediately above these ribs and like the ribs form a guide to engage the top surfaces of the arms of the die, so as to hold the latter against turning, but in a manner to permit of longitudinal 25 movement of the dies to and from each other.

Each of the sides 13 are provided with elongated openings 25 to receive screw bolts 16 that are mounted for slidable movement therein and serve to rotatably support the 30 dies, positioned thereon between the said sides. In the rotary adjustment of the dies, they together with the screw bolts, would first be moved outward with respect to each other until the ends of their arms cleared 35 the guide plates 24 and would then be rotated to any desired position, after which the dies would again be set up in position between the guides 23 and 24.

The means for longitudinally adjusting the 40 dies, is alike for each die, and includes a slotted bearing 26 formed on the top side of the cylindrical extension 11 and bored to receive adjusting screw 27 upon the inner threaded end of which is a tapped shoe 28 for threadable engagement with the screw so that with 45 the turning of the screw the shoe will be moved longitudinally against the surface 22 of the die in a way to move the same longitudinally between the sides and cause the screw bolt to slide within the slot of the sides. In this respect, it will be noted that each 50 screw 27 is provided with a pin 30 adjacent one end and adapted to be moved with the longitudinal movement of the screw through slot 29 so that after passing through the slot 55 they will ride, with a turn of the screw, upon the inner end of the bearing and serve to hold the screw against outward longitudinal movement, thereby forcing the shoe and the die with which it engages, in. When it is desired to withdraw the dies, it is done by turning the screws back so that the pins will register with the slots which permits of a quick 60 sliding movement of the screws and dies, until the annular flange upon the shoes are

brought to bear against the end of the bearing.

Having thus described my invention, what I claim and desire to obtain by Letters Patent, is:

1. A thread cutting stock and die comprising a stock having an opening therethrough and oppositely disposed handles, spaced apart parallel side walls extending from one face of the stock on opposite sides of said opening and having aligned slots therein, pivotal members adjustably mounted in said slots, a pair of multiple point dies rotatably mounted upon the pivotal members between the said sides, a shoe seated against the side of each of said dies, the said stock including a slotted bearing on each end, a screw threadably engaging each of said shoes and rotatably and slidably mounted in the slotted bearings to adjust the dies toward each other, the said screws carrying a projected pin adapted to slide through the slot and to engage the end of the bearing for quick adjustment of the dies. 70

2. A thread cutting stock and die comprising a stock having a pipe supporting opening therethrough and oppositely disposed handles, opposed parallel side walls extended from one side of the stock and adjacent said opening, opposed aligned slots in said side walls, pivotal members mounted for sliding movement in said slots, a pair of multiple point dies rotatably mounted upon the pivotal members between said sides and including relatively long extended threading arms 90 having parallel side and edge portions, guides in opposite side portions of the stock adjacent said opening to receive the arms of the dies and to hold the same in alignment against both rotary and sidewise movement, and means for adjusting said pivotal members and dies to and from each other to position the threaded arms of the dies in the 95 said guides. 100

3. A thread cutting stock and die comprising a stock having a pipe receiving opening therethrough and oppositely disposed handles, parallel side walls extended from one side of the stock and adjacent said opening, opposed slots in said side walls, pivotal members mounted for sliding movement in said slots, a pair of multiple point threading dies rotatably mounted on the pivotal members between said sides and including extended arms having parallel side and edge portions, aligned sockets formed between said side walls to receive and hold the arms of the dies in alignment against both rotary and sidewise movement, and means for adjusting said pivotal members and dies to and from each other to move the threading arms of the dies in and out of the said sockets. 110

4. A thread cutting stock and die comprising a stock having a pipe receiving opening therethrough, parallel side walls extended 120

from the face of the stock adjacent the opening and having longitudinal guide ribs along their inner opposed faces, plates secured to said sides to form aligned sockets, opposed 5 slots formed in said side walls, pivotal members mounted for sliding movement in said slots, a pair of multiple point threading dies rotatably mounted on the pivotal members between said sides and including relatively 10 long arms to engage said aligned sockets formed between said side walls and pivotal members to hold the arms of the dies against both rotary and sidewise movement, and means for adjusting said pivotal members 15 and dies to and from each other to position the threading arms of the dies in the said sockets.

Signed at Bridgeport, in the county of Fairfield and State of Connecticut, this 10th 20 day of March, A. D. 1931.
